ATTORNEY

UNITED STATES PATENT OFFICE.

MICHAEL C. DILLON, OF WILLISTON, NORTH DAKOTA.

WRENCH.

1,371,873.

Specification of Letters Patent. Patented Mar. 15, 1921.

Application filed April 6, 1920. Serial No. 371,598.

To all whom it may concern:

Be it known that I, MICHAEL C. DILLON, a citizen of the United States of America, residing at Williston, in the county of Williams and State of North Dakota, have invented new and useful Improvements in Wrenches, of which the following is a specification.

This invention comprehends the provision 10 of a quick acting wrench, wherein the handle is provided with a spring actuated rod which controls the pivoted locking element from the movable jaw, in a manner whereby the latter can be easily and quickly adjusted with relation to the fixed jaw, subsequently locking it in a given position.

The nature and advantages of the invention will be better understood when the following detailed description is read in connection with the accompanying drawings, the invention residing in the construction, combination and arrangement of parts as claimed.

In the drawings forming part of this application, like numerals of reference indicate similar parts in the several views, and wherein:

Figure 1 is a longitudinal sectional view of the wrench showing the parts in active 30 position.

Fig. 2 is a similar view showing the locking parts in position for adjusting the movable jaw.

Fig. 3 is a sectional view taken on the line 35 3—3 of Fig. 1.

Referring to the drawings in detail, 30 indicates the handle of the wrench, at one end of which is arranged a fixed jaw 31. The handle is provided with a looped extension 40 32 through which slides the shank 33 of the movable jaw 34. The lower longitudinal edge of the shank 33 is notched as at 35. The notches 35 are adapted to receive the offset rounded extremity 36 of the pivoted locking element 37 which has one end 38 weighted. The weighted extremity 38 normally maintains the offset portion 36 of the locking element positioned in one of the notches 35 of the shank 33.

For the purpose of effecting the release 50 of the shank 33 when it is desired to adjust the movable jaw with relation to the fixed jaw, I provide a rod 40 arranged to reciprocate in an opening 41 in the handle 30.

One end of the rod 40 is connected as at 42 with a substantially L-shaped lever 43 piv-

oted above the handle as at 44 and having one of its branches disposed at one side of the handle as shown. The free end of the rod 40 is provided with a straight passage 60 45 having an inclined surface 46. As shown in Fig. 1 when the bars are arranged in active position, the locking element 37 rests upon the straight surface 45 of the rod 40, while the inclined surface 46 is arranged in 65 juxtaposition to the weighted end 38 of the locking element. The spring 47 has one end secured to the rod 40 and the opposite end to the handle 35 to hold the rod 40 normally in the position shown in Fig. 1. 70 When it is desired to effect the release of the shank 33, and thus permit movement of the jaw 34 with relation to the jaw 31, the lever 43 moves toward the handle 30 thereby exerting a pressure upon the rod 40. As the 75 rod moves in the direction of the lever 43, the inclined surface 46 is brought into engagement with the weighted extremity 38 of the locking element, moving the latter on its pivot to disengage the offset extremity 36 80 from the shank 33. This adjusted position of parts is clearly shown in Fig. 2. When pressure is released from the lever 43, the spring 47 functions to move the rod within the handle toward the jaw 31, or in other 85 words to return the rod to its normal position. As the inclined surface 46 is moved away from the weighted extremity 38 of the locking element, said extremity serves to move the element upon its pivot to return 90 the offset extremity 36 into one of the notches 35. The wrench is very simple in construction and can be readily and easily manipulated as the occasion requires.

While it is believed that from the foregoing description the nature and advantages of the invention will be readily apparent, I desire to have it understood that I do not limit myself in the details shown and described, and that such changes may be 95 resorted to when desired as fall within the scope of what is claimed.

What I claim is:

1. A wrench comprising a handle having a fixed jaw, a movable jaw including a 105 shank arranged parallel to the handle, a locking element pivoted on said handle and designed to coöperate with said shank for holding the movable jaw in a given position, a spring-actuated rod for effecting the release of said movable jaw, said rod being 110 mounted for sliding movement longitudi-

nally of the handle and having a cam-like surface coöperating with the pivoted locking element, and means for sliding said rod.

2. A wrench comprising a handle having a fixed jaw, said handle being recessed longitudinally, a movable jaw including a shank arranged parallel to the handle, a locking element pivoted within the recess formed in the handle and designed to engage the shank to hold the movable jaw in a given position, a spring-actuated rod for

effecting the release of the said movable jaw, said rod being arranged in the recess of the handle and mounted for sliding movements therein, a cam-like surface formed on the rod and coöperating with the pivotal locking element, and a manipulating element pivoted on the handle and connected with said rod for sliding the latter. 15

In testimony whereof I affix my signature. 20

MICHAEL C. DILLON.
